AIR CLEANER

Auguste Louis René Bernard, Rueil-Malmaison,
France; Renée Bernard (nee Bourronville)
executrix of said Auguste Louis René Bernard,
deceased

Application October 15, 1934, Serial No. 748,412
In Belgium October 16, 1933

6 Claims. (Cl. 183—77)

The present invention relates to devices for the purifying of air fed to an internal combustion engine for permitting the combustion of fuel therein.

5 The object of the present invention is to provide a device of this kind which is simpler than those used up to the present time.

The essential feature of the present invention consists in the provision of a filter or strainer 10 carried by an organ rotated by the engine.

In a preferred embodiment of the invention this organ consists of the fly-wheel of the engine.

15 Preferably, according to the present invention, this filter is so arranged as to be located, at least partly within the limits of the space occupied by the fly-wheel in projection in the direction of the axis of said fly-wheel, and in such manner that the air to be fed to the engine flows through said filter in a direction substantially parallel to said 20 axis.

Whereas this filter may be arranged laterally to the fly-wheel, or in juxtaposition therewith, yet it is preferable to have the filter occupy, with respect to the fly-wheel, a position corresponding 25 to that of the web provided in a great number of fly-wheels.

Of course, in this case, the peripheral portion of the fly-wheel is connected to the hub thereof not through a solid web but through arms between 30 which are provided passages for the flow of the air to be fed to the engine through the filter.

Advantageously, the filter is adapted to be removed toward the front, so as to facilitate the cleaning thereof.

35 Preferably, in order to obtain a purification as perfect as possible, I combine with the filter a centrifugal purifier through which the air to be fed to the engine flows in a direction opposite to that of the centrifugal force. This purifier is advantageously mounted in front of the filter and it may be carried by the rotary organ that carries the filter.

When the engine includes a cooling system, such 45 for instance as a radiator, through which air is sucked in by a centrifugal fan also carried by the fly-wheel, it is advantageous to arrange the centrifugal purifier above referred to laterally to this fan, preferably on the external side of the fly-wheel, that is to say on the side opposite to that which is closer to the engine.

I may also add to the purifier above mentioned a second purifier of the centrifugal kind, which is preferably given a diameter of the same order of 50 magnitude as the first purifier, and which is asso-

ciated with the first one, being for instance carried by the same rotary organ as the filter.

Anyway, the system constituted by the combination of both purifiers is so arranged that air flows along a sinuous path, first moving toward the axis of rotation (between the fins or the like of the first centrifugal purifier), then moving away from this axis, then again toward the axis (between the fins or the equivalent of the second centrifugal purifier) and finally toward the passages leading to the filter. 5

If, when issuing from the simple or double centrifugal purifying device above referred to, air (which is already freed from dust to a considerable degree) is moving toward the outer face of the 15 fly-wheel, I preferably provide a partition or wall closing this external face of the fly-wheel and deflecting said air toward the central part of the fly-wheel so as to cause it to flow through the filter which is disposed in this central part. 20

It will be readily understood that with such a system including three stages of purification, the most part of the impurities is stopped by the first centrifugal purifier. The second purifier will stop and retain in its peripheral portion a great 25 portion of the remaining impurities, which will be removed by cleaning this purifier at suitable intervals. Finally, the filter will stop the particles that shall have passed through the two purifiers and will complete a practically perfect removal of 30 dust from the air that is to be fed to the engine.

As the filter, with such an arrangement, will be called upon merely to complete the purification, dirt will but very slowly accumulate thereon so that this filter, if cleaned at suitable intervals 35 of time (which may be relatively long), will never exert an exaggerated resistance to the flow of air as it is the case, after a very short time of working, with filters through which the air to be fed to the engine passes directly from the outside. 40

A preferred embodiment of the present invention, will be hereinafter described, merely by way of example, with reference to the accompanying drawing, and in which:

The only figure is a cross sectional view of the 45 purifying device according to the present invention.

In this embodiment of the invention, the filter 1 is carried by a fly-wheel 2 having a rim which is relatively large in the radial direction. 50 This rim is connected to the hub of the fly-wheel through arms 6.

In this rim are provided, in the usual manner, the conduits of centrifugal fan 5, which is to suck in the cooling air that is to flow through 55

5 radiator 4. These conduits are for instance provided with small blades for driving the cooling air. They are connected, on the internal side of the fly-wheel, with an annular orifice 7 of a chamber 8 itself connected with the air outlet of the radiator.

10 Fly-wheel 2 carries, on the side of its external face, the centrifugal purifier 3. This purifier is provided, in the usual manner, with passages, 15 provided for instance between small blades, leading toward the central part of the fly-wheel. These passages are of relatively short length (for instance equal to a quarter of the radius of the fly-wheel) and they are curved in such manner as to open into the external face of the fly-wheel at their end which is closer to the axis of rotation.

20 In order to facilitate the construction of the device, these passages are obtained by securing to the peripheral portion of the external face of the fly-wheel an annular plate 9 which constitutes one of the walls of these passages and the inner edge of which limits, on the outside, the annular orifice 10 of these passages toward the 25 external face of the fly-wheel.

30 The fly-wheel is further provided, along the inner edge of this annular orifice 10, with an annular deflector 11 (preferably rigid with plate 9) adapted to deflect toward the periphery the stream of air that has passed through purifier 3.

35 Advantageously, between plate 9 and deflector 11, I provide small blades 12 adapted to keep in rotation the stream of air that has passed through purifier 3.

40 I fix to the external face of the fly-wheel thus devised a kind of drum 13, for instance of stamped sheet metal, having a peripheral portion which may be cylindrical and of a diameter equal to that of the fly-wheel. This peripheral part is connected to the external edge of plate 9 and it carries a circular flange extending in front of the external face of the engine so as to deflect the air that has passed through the spaces between blades 12 again toward the axis of rotation through annular passage 14 existing between said flange and deflector 11.

45 Within drum 13 and in the peripheral part thereof I provide blades 15 adapted to coact with blades 12 for keeping the air present in this drum in rotation.

50 This annular passage 14 which is formed by the deflector 11 and the drum 13 constitutes the second centrifugal purifier since the air is forced to flow through this passage from the periphery 55 of the flywheel toward the center thereof. Such dust particles which have not been removed from the air current by the first centrifugal purifier, which is formed by the passage 3, are subjected to the centrifugal purifying effect of this second 60 rotating passage 14.

65 If the device included only these elements, passage 14 would communicate directly with the space existing between the arms 6 of the fly-wheel, and it would suffice to provide an annular partition 16 limiting, between the frame 17 of the engine and the internal edge 18 of the rim, a chamber 19 for collecting the air to be fed to the engine, which is subsequently led to the engine proper through conduits 20.

70 But, in order to increase the purifying action of filter 1, I advantageously position this filter in the circular space existing inside annular deflector 11. Owing to the relatively small radial dimensions of the passages of purifier 3, this circular space is of relatively large diameter, for

75 instance three quarters of the diameter of the fly-wheel.

The filter or strainer 1 is preferably given the form of an annular plate consisting of at least one thickness of a filtering material (for instance a fabric) stretched by means of an external ring adapted to be inserted in a suitable housing provided in the fly-wheel.

80 The stream of air that has flown through the two purifiers 3 and 14 arranged in series is thus compelled to flow through filter 1 in order to penetrate into chamber 19.

85 In order to permit of readily taking the device to pieces, I provide means for permitting removal of drum 13 with a view to cleaning and 15 removing the filter.

90 In this case, said drum 13 is provided with springs or equivalent means 22 adapted to exert a certain pressure on the filter so as to maintain it in its housing when the drum is fixed in position on the flywheel.

95 The removable arrangement above referred to is advantageously obtained by providing a hole in the central part of drum 13, and by applying against the edges of said hole a milled nut 23 25 adapted to be screwed on an extension 24 of the engine shaft in such manner that when said nut is tightened it exerts on drum 13 a pressure that applies the edges of said drum against those of the annular plate 9.

30 As for the filter, it is provided with a central hole adapted to fit on a sleeve 25 leaving a passage for the extension 24 above referred to.

35 It will readily be understood that when drum 13 is removed it is possible, by catching the end 35 of sleeve 25, to remove the filter with a view to cleaning it.

40 Besides, as above explained, it will not be necessary to perform this cleaning operation very often.

45 On the contrary, drum 14, in the peripheral part of which dust is deposited which has passed through purifier 3 should be cleaned more frequently.

50 This dust will adhere to this peripheral part 45 against which it shall have been thrown by the centrifugal part.

55 Besides, adhesion can be improved by coating this peripheral part of the drum with a liquid or pasty material, such as oil.

60 It should be noted that when drum 13 is removed, if dust drops from said drum, it cannot penetrate into the engine, owing to the presence of the filter.

65 In the case of the engine being provided with a crank for starting the engine, as shown at 26, it will be readily understood that this crank can be fixed, on the outside of the device above described, to the extension 24 above referred to.

70 Of course, the filter, instead of being of flat 60 shape, might be of frusto-conical or corrugated shape, or it might be provided with pleats, either radial or concentric.

75 While I have, in the preceding description, disclosed what I deem to be a practical and efficient 65 embodiment, it should be understood that I do not wish to be limited thereto as there might be changes made in the arrangement, disposition and form of the parts without departing from the principle of the present invention as comprehended within the scope of the appended claims.

80 What I claim is:

85 1. In connection with an internal combustion engine having a fly-wheel, a filter for the air to be fed to said engine carried by said fly-wheel,

- and centrifugal purifying means mounted in series with said filter in front thereof.
2. In connection with an internal combustion engine having a fly-wheel, a filter for the air to be fed to said engine carried by said fly-wheel and at least one centrifugal purifying device carried by said fly-wheel and connected in series with said filter, in front thereof.
3. In connection with an internal combustion engine having a fly-wheel, a filter for the air to be fed to said engine carried by said fly-wheel and two centrifugal purifying devices carried by said fly-wheel in series with each other and with said filter, in front thereof.
- 15 4. In connection with an internal combustion engine, the combination of a fly-wheel having a rim, a hub and arms connecting said rim with said hub, a centrifugal purifier carried by said rim having passages the inlets of which are provided on the periphery of said rim and the outlets of which open in a peripheral direction into the external face of said fly-wheel, a second purifier, also carried by said fly-wheel, having passages leading toward the axis of said fly-wheel 20 along the external face thereof, and a filter mounted in said fly-wheel between said rim and said hub, so that air flowing out from said second purifier is caused to flow through said filter.
- 25 5. In connection with an internal combustion engine, the combination of a fly-wheel having a
- rim, a hub, and arms connecting said rim with said hub, an annular plate fixed to said rim in front of the periphery thereof, a curved flange carried by the external face of said rim so that the peripheral portion of said rim, said plate and said flange form an annular curved passage the inlet and the outlet of which are both directed toward the periphery of the fly-wheel, means in said passage for exerting a centrifugal action on the air flowing therethrough, a drum connected 10 to the outer edge of said annular plate, and covering the external face of said fly-wheel, so as to form a passage connected in series with the first mentioned passage leading toward the center of the fly-wheel, means in the last mentioned passage for exerting a centrifugal action on the air flowing therethrough, and a filter directly connected with said last mentioned passage and mounted in said fly-wheel between said rim and said hub, whereby air coming from said second 15 mentioned passage is forced to flow through said filter before being allowed to flow out in the spaces provided between said arms between said rim and said hub.
6. A combination according to claim 5 in which 20 said filter is removably mounted in said fly-wheel, said drum being removably fixed on said annular plate, so as to permit of removing and cleaning the filter.

AUGUSTE LOUIS RENÉ BERNARD. 30
